UNITED STATES PATENT OFFICE

2,102,391

REFRIGERATING MACHINE

Christian Steenstrup, Schenectady, N. Y., assignor to General Electric Company, a corporation of New York

Original application June 14, 1934, Serial No. 730,589. Divided and this application April 13, 1935, Serial No. 16,161

7 Claims. (Cl. 62—116)

My invention relates to refrigerating machines, and is a division of my co-pending application Serial No. 730,589, filed June 14, 1934.

It is an object of my invention to provide a refrigerating machine having a motor and compressor arranged within an insulated casing and having a lubricating system utilized to dissipate heat generated by the motor and compressor exteriorly of the insulated casing.

Another object of my invention is to provide a refrigerating machine for cooling a cabinet having a motor and compressor casing enclosed within the thermal insulation of the cabinet and provided with an improved system for dissipating heat from the machine.

Further objects and advantages of my invention will become apparent as the following description proceeds, and the features of novelty which characterize my invention will be pointed out with particularity in the claims annexed to and forming a part of this specification.

For a better understanding of my invention reference may be had to the accompanying drawings in which Fig. 1 is an elevation view, partly in section, of a household refrigerator, embodying my invention; Fig. 2 is a sectional perspective view of the motor and compressor unit of the refrigerating machine shown in Fig. 1; and Fig. 3 is a sectional view of the compressor taken on the line 3—3 of Fig. 2.

Referring now to Fig. 1, I have shown a household refrigerator cabinet 10 mounted on legs 11 and comprising inner and outer metallic walls or shells 12 and 13 respectively, the inner wall 12 being the liner for the refrigerator compartment, and the outer wall 13 being provided with a top wall or plate 14 having a dome 14a thereon. The refrigerator is provided with a door affording access to the compartment. Between the inner and outer walls at the top of the cabinet and within the dome 14a is arranged a motor and compressor casing 15 supported on channel irons 16 secured across the top of the cabinet, the ends of these channels being resiliently attached to the cabinet to minimize the transmission of vibration to the cabinet. A motor and compressor unit 17 is arranged within the casing 15 and supplies compressed gaseous refrigerant through a conduit 18 to a condenser 19 which comprises a sinuous conduit arranged between the inner and outer walls 12 and 13 and clamped in contact with or otherwise secured to the inner surfaces of three sides of the outer wall 12. Gaseous refrigerant in the condenser 19 is cooled and liquefied by the circulation of air about the outer walls of the

cabinet. This arrangement of a condenser on the outer walls of a refrigerator cabinet is disclosed and claimed in my Patent No. 1,985,065, granted December 18, 1934, and assigned to the General Electric Company, assignee of my present invention.

The liquid refrigerant flows from the condenser 19 through a conduit 20 to a receiver or float chamber 21 arranged in the insulation between the inner and outer walls of the cabinet. When a predetermined quantity of liquid has collected within the chamber 21 a float 22 rises and a quantity of liquid flows through a connection 23 to an evaporator 24 having headers 25 and 26 connected by a vapor conduit 27. Liquid refrigerant within the evaporator 24 is vaporized upon absorption of heat from the refrigerator compartment and collects within the headers 25 and 26 above the level of liquid refrigerant therein from whence it is withdrawn through a suction connection 29 by the compressor within the casing 15. The upper end of the suction connection 29 opens into the casing 15 above a body of oil 30 in the bottom of the casing. All the space within the inner and outer metallic walls of the refrigerator cabinet and surrounding the casing 15, the receiver 21, and the other parts of the refrigerating machine is filled with heat insulating material. The insulating material in addition to thermally insulating the refrigerator cabinet and the several parts of the refrigerating machine also serves to minimize the transmission to the cabinet walls of any sound produced by the operation of the motor and compressor within the casing 15. The body of oil 30 within the casing 15 is utilized for lubricating the motor and compressor, unloading the compressor, and dissipating the heat generated within the motor and compressor, in a manner which will be hereinafter described.

Referring now to Fig. 2, I have shown a compressor casing 15 comprising an upper shell 32 and a lower shell 33 fitted within the upper shell and welded thereto at 34 to provide a gas-tight joint. Within the casing 15 is arranged a motor comprising a stator 35 provided with windings 36 and a rotor 37 mounted on a shaft 38 journaled in a block 39. The stator 35 is secured to the block 39 by a base ring or end shield 40, which is an annular channel covering the lower end of the winding 36 and welded to the block 39 at 41, the stator being secured to the ring by bolts 40a. The stator 35 and the base ring 40 are surrounded by a corrugated baffle 42 which frictionally supports the motor and compressor within the casing 15. In assembling the motor within

the casing 15 the baffle 42 is placed around the stator 35 and the base ring 40 and the assembly is forced into the upper shell 32, the corrugated baffle 42 being of such dimensions as to provide 5 a close fit and to retain the motor assembly securely in position within the casing 15. The baffle 42 provides a plurality of passages between the stator and the walls of the casing 15. The baffle 42 is constructed to be sufficiently yielding to allow 10 wide tolerances in the machining operations on the parts of the unit, the deformation of the baffle when the motor is mounted in the shell permitting some variation in the diameters of the shell 32 and the stator 35.

15 A compressor for the refrigerating machine and an oil pump are secured below the driving motor. In the construction shown a compressor block 43 is welded or otherwise secured to the block 39 as shown at 44, and below this is secured 20 a bearing block 45 within which is journaled the shaft 38 and below the bearing block 45 is arranged an oil pump block 46 and a cover plate 47. The refrigerant compressor comprises a cylindrical bore 48 in the block 43, which is arranged 25 eccentrically with respect to the axis of the shaft 38. Within the bore 48 and formed integrally with the shaft 38 is a cylindrical compressor rotor 49 which is concentric with the shaft 38 and is mounted so as to run in contact with the walls 30 of the bore 48 as shown at 50. The compressor is provided with an intake port 51 and an exhaust port 52 arranged near the point of contact 50 and on either side thereof. Two blades 53 are 35 radially and slidably mounted diametrically opposite each other within the compressor rotor 49. During the operation of the compressor the rotor 49 is driven by the motor, and these blades slide in and out of the slots 53a so that they run in contact with the walls of the cylindrical bore 48. 40 Gaseous refrigerant which enters the intake port 51 from the casing 15 is compressed by the blades 53 within the crescent-shaped space formed between the rotor 49 and the walls of the cylindrical bore 48. The leading edges of the blades 53 are 45 slightly rounded as indicated at 53b in order that the pressure of the compressed gas within the cylinder will provide a small radial component of force tending to move the blades 53 away from the cylinder walls. The trailing edges of the 50 blades are relieved to reduce friction. The compressed refrigerant is forced out of the exhaust port 52 upon clockwise rotation of the member 49, the compressed refrigerant passing through an outlet check valve 54, and thence through the 55 conduit 18 to the condenser. The conduit 18 is connected to a block 54a which is secured to the block 43 by bolts 55, and the outlet check valve 54 is clamped between the block 43 and the block 54a. The intake port 51 is provided with a connection 56 opening into the casing 15 above the body of oil 38 therein and is provided with a screen 57 to prevent particles of foreign matter 60 from entering the compressor chamber.

An oil lubricating system for the motor and 65 compressor is arranged so that the refrigerant compressor is loaded and unloaded in response to the pressure of the lubricating oil which is built up as the motor comes up to speed, and a further arrangement is provided so that the pressure of the oil is substantially independent of the viscosity thereof. The oil circulated is cooled and utilized to dissipate the heat generated by the motor and compressor to prevent overheating of the refrigerating machine.

70 In the construction shown I provide an oil

pump including a cylindrical bore 58 in the block 46 slightly eccentric with respect to the shaft 38, the walls of the bore 58 being in contact with the shaft 38 at one side. Within a diametrical slot in the shaft 38 is mounted a slidable blade 59 which 5 projects on either side of the shaft and has a length almost equal to the diameter of the bore 58, its length being determined by the eccentricity of the shaft and the bore 58. The slight shortening of the blade necessary because of the eccentricity of the bore is not sufficient to materially impair the satisfactory operation of the pump. The shaft 38 and the blade 59 have bearing surfaces in contact with the cover plate 47. A plunger 60 mounted in the shaft 38 and pressed 10 against the blade 59 by a spring 61 maintains the blade 59 in contact with the cover plate. Oil is admitted to the pump chamber through a port 62 passing through the plate 47 and the block 46, a screen 63 being arranged over the entrance 20 to the port on the bottom of the plate 47 to prevent the admission of foreign matter to the pump chamber.

Oil is discharged from the pump through a port 64 and passes upwardly through a passage 25 65 in the block 45 and enters a counterbore 66 in the top of the block 45, eccentric with respect to the shaft 38 and the compressor rotor 49. From the counterbore 66 the oil flows into the slots 53a in which the blades 53 are arranged. A 30 counterbore 67 is provided in the block 39 above the bore 48 to receive the oil discharged from the slots 53a. This bore is also eccentric with respect to the shaft 38 and is arranged in the same relation to the shaft 38 as the counterbore 66. When the refrigerating machine is started and is coming up to speed oil pressure is gradually built up by the oil pump. The oil flows into the slots 53a and when sufficient pressure has been developed it overcomes the friction 35 between the blades 53 and the slots 53a of the bore and also the radial component of pressure acting on the leading edges of the blades and moves the blades 53 into contact with the walls of the bore 48 thereby loading the compressor. The counterbores 66 and 67 serve to lubricate the bearing surfaces of the compressor rotor 49, and also effectively seal the rotor against leakage of compressed refrigerant. It will be noted that, as the rotor 49 turns, the eccentric counterbores will have a wiping action on the end surfaces thereof, and since the counterbores are filled with oil under pressure, the oil will lubricate the surfaces of the rotor and will also seal the rotor against leakage of compressed refrigerant. Referring particularly to Fig. 3, the counterbores 66 and 67 are arranged so that as the blades 53 move toward the exhaust port 52 the distance between the counterbores and the periphery of the rotor 49 increases. In this manner increased resistance to leakage of compressed gas is provided as the pressure of the gas is increased. When the motor is stopped the oil pressure decreases and finally when the blades 53 pass the point 50 and are pressed toward the center of the rotor 49 there is no longer sufficient oil pressure to force them out of the slots toward the walls of the bore 48, and the compressor is then unloaded since the intake and exhaust ports are in communication. The friction 40 of the blades 53 in the slots 53a together with the pressure of the compressed gas on the relieved leading edges of the blades is sufficient to prevent the blades from being thrown out against the walls of the bore 48 centrifugally 45 50 55 60 65 70 75 80 85 90 95 100

with sufficient force to compress gas in the cylinder at speeds below that at which it is desired to unload the compressor.

The viscosity of the lubricating oil may change due to changes in temperature and, for this reason, a change in the pressure developed by the oil in the lubricating system may result from a change in the temperature of the oil. In order to maintain the pressure substantially constant regardless of changes in the viscosity of the oil, I provide a sharp-edged orifice 68 formed in a cup-shaped insert 69 which is secured to the block 43 and communicated with the upper counterbore 67 through passages 70 and 71. The passages through which the oil flows before reaching the orifice are made of a sufficiently large cross-section to avoid any substantial resistance to the flow of oil. The resistance to the flow of oil necessary for the building up of the desired pressure is supplied by the orifice. Flow of fluid through a sharp-edged orifice is independent of the viscosity of the fluid and hence the pressure of the oil between the pump, which supplies the oil at constant volume, and the orifice will not change with varying viscosity of the oil. The provision of a sharp-edged orifice through which oil flows in an oil operated compressor unloader in order to minimize the effect of changes in viscosity of the oil upon the operation of the unloader is not my invention, but is the invention of Harley H. Bixler and is described and claimed in his copending application, Serial No. 1,337, filed January 11, 1935, and assigned to the General Electric Company, the assignee of my present invention.

Since the oil is under pressure when it passes through the orifice any refrigerant which is entrained therein will tend to vaporize on passing through the orifice. In order to prevent the transmission of pulsations from the oil pump, I provide a surge chamber 72 on the discharge side of the orifice 68 which collects a portion of the vaporized refrigerant. Refrigerant carried by the oil will be vaporized on passing through the orifice and a body of vapor will collect in this chamber and provide a cushioning effect which will damp out pulsations produced by the oil pump.

The oil discharged from the orifice 68 passes into a conduit 31 the major portion thereof being a sinuous coil in contact with the inner surface of the outer metallic wall 13 of the refrigerator cabinet, so that the wall 13 is utilized as a heat dissipating surface to cool the oil. The oil thus cooled then enters the casing 15 through a connection 73 from which it is discharged into a depression 74 in the top of a bell-shaped shell or hood 75 spaced from the casing 15, and secured on the stator 35. The shell 75 is fitted on the upper end of the stator and encloses the upper end of the motor. Oil fills the depression 74 and flows uniformly from the rim of the depression and over the entire surface of the shell 75 absorbing heat therefrom. It then flows downwardly between the casing and the laminations of the stator 35 through the corrugations of the baffle 42 and cools the motor and the sides of the casing 15 before returning to the bottom of the casing. The space below the shell 75 and around the upper end of the motor is filled with refrigerant vapor which absorbs heat from the motor and is cooled as it is circulated over the under surface of the shell 75 by a fan 37a attached to the rotor 37. In this manner the top

of the motor is cooled by the oil flowing over the shell 75.

In the operation of the refrigerating machine, which I have described, when the motor is started the oil pump blade 59 will rotate in the cylindrical bore 58 and pump oil from the bottom of the casing 15 and discharge it through the passages 64 and 65 to the counterbore 66 and into the slots 53a filling the counterbore 67 and finally the passages 70 and 71. When the oil has filled these several passages it will be discharged through the orifice 68 and pressure will be built up between the orifice and the pump. When the motor attains approximately full speed the oil pressure will become sufficient to force the blades 53 radially outward, so that they run in contact with the walls of the bore 48, and gaseous refrigerant will be drawn from the casing 15 through the screen 57 to the inlet port 51 of the compressor. The refrigerant will be compressed by the rotating blades 53 and discharged through the port 52 and the valve 54. The refrigerant compressed is discharged directly into the conduit 18 and flows to the condenser 19 where it is cooled and liquefied, the outer wall of the cabinet being utilized as a heat dissipating surface over which air circulates by natural draft. Liquid refrigerant then passes upwardly through the conduit 20 and enters the float chamber or receiver 21 from which it is discharged in predetermined quantities and enters the evaporator 24. Liquid refrigerant within the evaporator 24 is vaporized upon absorption of heat from the refrigerator compartment and collects in the headers 25 and 26 and finally returns through the conduit 29 to the casing 15. The direction of flow of the refrigerant as described is indicated by the solid arrows in the drawings. The oil which is discharged through the orifice 68 enters the surge chamber 72 where any gas therein collects to form a cushioning chamber or pulsation damper. The oil flows into the conduit 31 and is cooled as it passes through the coils of the conduit 31 which are in contact with the outer wall 13 of the refrigerator cabinet, the wall 13 being cooled by natural draft. The cooled oil is then discharged through the connection 73 and flows into the depression 74 uniformly over the entire surface of the shell 75 and through the corrugations of the baffle 42. In this manner heat generated by the motor is absorbed by the oil before it returns to the bottom of the casing 15 from which it is again circulated by the oil pump. The direction of flow of the oil is indicated by the dotted arrows in the drawings.

While I have shown a particular embodiment of my invention in connection with a household refrigerating machine, other applications will readily be apparent to those skilled in the art, and I do not, therefore, desire my invention to be limited to the specific embodiment shown and described, and I intend in the appended claims to cover all modifications within the spirit and scope of my invention.

What I claim as new and desire to secure by Letters Patent of the United States is:

1. A refrigerating machine comprising a closed casing and including an electric driving motor, means in said casing for producing circulation of refrigerant, a cabinet for said machine including a metal outer shell and an inner liner spaced therefrom and insulation filling the space therebetween, said inner liner forming a compartment having a door opening affording access thereto, said casing being imbedded in the insulation be-

tween the top wall of said metal outer shell and the top wall of said inner liner, and means including said refrigerant circulating means for cooling said compartment.

5. 2. A refrigerating machine comprising a closed casing having a compressor and an electric driving motor therefor arranged therein, a cabinet for said machine including a metal outer shell and an inner liner spaced therefrom and insulation filling the space therebetween, said inner liner forming a compartment having a door opening affording access thereto, said casing being imbedded in the insulation between the top wall of said metal outer shell and the top wall of said inner liner, and means including said compressor for cooling said compartment.

3. A refrigerating machine comprising a closed casing having a compressor and an electric driving motor therefor arranged therein, a cabinet for said machine including a metal outer shell and an inner liner spaced therefrom and insulation filling the space therebetween, said inner liner forming a compartment having a door opening affording access thereto, the top wall of said metal outer shell having a dome extending upwardly therefrom, said casing being arranged in said dome and imbedded in the insulation between said metal outer shell and said inner liner, and means including said compressor for cooling said compartment.

4. A refrigerating machine comprising a closed casing having a compressor therein, a cabinet for said machine including a metal outer shell and an inner liner spaced therefrom and insulation filling the space therebetween, said inner liner forming a compartment having a door opening affording access thereto, said casing being imbedded in the insulation between the top wall of said metal outer shell and the top wall of said inner liner, a condenser carried by said metal outer shell so as to utilize the surface thereof to dissipate heat from said condenser, and means including said compressor and said condenser for cooling said compartment.

45. 5. A refrigerating machine comprising a closed casing having a compressor therein, a cabinet for said machine including a metal outer shell and an inner liner spaced therefrom and insulation filling the space therebetween, said inner liner forming a compartment having a door opening affording access thereto, said casing being

imbedded in the insulation between the top wall of said metal outer shell and the top wall of said inner liner, a condenser carried by said metal outer shell so as to utilize the surface thereof to dissipate heat from said condenser, means for lubricating said compressor and for circulating lubricant from said casing in heat exchange relation with said metal outer shell for dissipating heat from said casing, and means including said compressor and said condenser for cooling said compartment.

5. 6. A refrigerating machine including a motor and compressor driven thereby, a closed casing for said motor and said compressor, a cabinet for said machine including a metal outer shell and an inner liner spaced therefrom and insulation filling the space therebetween, said inner liner forming a compartment having a door opening affording access thereto, said casing being imbedded in the insulation between the top wall of said metal outer shell and the top wall of said inner liner, means circulating lubricant for lubricating said motor and said compressor, means including a conduit communicating with said lubricating means and arranged in contact with said metal outer shell for cooling the lubricant circulated by said lubricating means, and means including said compressor for cooling said compartment.

7. A refrigerating machine including a motor and a compressor driven thereby, a closed casing for said motor and said compressor, a cabinet for said machine including a metal outer shell and an inner liner spaced therefrom and insulation filling the space therebetween, said inner liner forming a compartment having a door opening affording access thereto, said casing being imbedded in the insulation between the top wall of said metal outer shell and the top wall of said inner liner, means circulating lubricant for lubricating said motor and said compressor, means including a conduit communicating with said lubricating means and arranged in contact with said metal outer shell for cooling the lubricant circulated by said lubricating means, a condenser communicating with said compressor and arranged between the insulation and the inner surface of said metal outer shell in contact with the latter, and means including said compressor and said condenser for cooling said compartment.

CHRISTIAN STEENSTRUP.
